[57] CLAIM

The ornamental design for a backpacker's tent, substantially as shown and described.

DESCRIPTION

FIG. 1 is a perspective view of the front and right side of a backpacker's tent in accordance with my design; FIG. 2 is an elevational view of the right side of the tent;

FIG. 3 is an elevational view of the rear of the tent;

FIG. 4 is a plan view of the tent; and

FIG. 5 is a bottom view of the tent.

Fig. 2
